(57) **CLAIM**

I claim the ornamental design for a food bowl, as shown and described.

DESCRIPTION

FIG. 1 is a top perspective view of a food bowl, according to my new design;

FIG. 2 is a bottom perspective view thereof;

FIG. 3 is a front view thereof;

FIG. 4 is a rear view thereof;

FIG. 5 is a right side view thereof, the left side view being a mirror image;

FIG. 6 is a top plan view thereof;

FIG. 7 is a bottom plan view thereof; and,

FIG. 8 is a cross-sectional view taken along a line 8-8 as seen in FIG. 6.

The evenly broken lines in the views depict environmental features of the food bowl that form no part of the claimed design. The dot-dash broken lines seen in FIGS. 2, 4, 7, and 8 represent boundaries of the claimed design, it being understood that the claimed design extends up to the boundary lines but does not include the boundary lines.
